UNITED STATES PATENT OFFICE.

ROBERT T. ROMINE, OF MOUNT CLEMENS, MICHIGAN.

SECTIONAL CAR CONTAINER.

Application filed June 15, 1927. Serial No. 199,100.

This invention relates to shipping containers or sections adapted particularly for shipment upon flat railway cars in sectional box car manner, and more particularly to containers which are adapted to be loaded onto or unloaded from the flat car at landing or loading docks in a railway transportation system.

An object of the invention is to provide sectional box car containers of improved construction capable of being rapidly and easily hoisted by means of a crane or lifted from beneath by means of a lift truck, and wherein the containers when in position upon the car preferably provide sectional overhead walkways of such improved construction as to permit trainmen to cross the tops of containers readily and safely during transit.

In the accompanying drawings, wherein like reference characters indicate similar parts in the several views:

Fig. 1 is a fragmentary side elevation of my improved sectional freight car showing one manner in which the containers are mounted upon the flat car floor or platform.

Fig. 2 is an end elevation of the construction shown in Fig. 1.

Fig. 3 is a fragmentary front elevation of one of the shipping containers or car sections of my invention.

Fig. 4 is a detail perspective view of one of the detachable legs for the container section of Fig. 3.

Fig. 5 is a view similar to Fig. 3 showing the legs of Fig. 4 assembled with the container.

Fig. 6 is an enlarged fragmentary detail, partly in section, of the container and detachable leg.

Fig. 7 is a fragmentary side elevation of a container section with its supporting legs in place.

Fig. 8 is an enlarged fragmentary detail of one corner of the container section of Fig. 7.

Fig. 9 is a fragmentary side elevation of my improved sectional freight car showing a modified form of container section and means for maintaining the section in position upon the flat car floor or platform.

Fig. 10 is an end elevation of the construction shown in Fig. 9.

Fig. 11 is an end elevation of the container section of Figs. 9 and 10 showing means for

supporting the section when removed from the freight car. 55

Fig. 12 is a fragmentary sectional view showing the manner in which the lower part of the container of Fig. 11 is constructed.

Fig. 13 is a fragmentary detail perspective view of the locking means for the containers 60 of Figs. 9 to 11 inclusive.

Before explaining in detail the present invention, and the method or mode of operation embodied therein, it is to be understood that the invention is not limited in its application to the details of construction and arrangement of parts illustrated in the accompanying drawings, since the invention is capable of other embodiments and of being practised or carried out in various ways. 70 Also, it is to be understood that the phraseology or terminology employed herein is for the purpose of description and not of limitation, and it is not intended to limit the invention beyond the terms of the several 75 claims hereto appended or the requirements of the prior art.

My improved container is illustrated, by way of example, in connection with a railway transportation system at a railway terminal, although it may be used at industrial plants or storage warehouses where large quantities of material are handled. For instance, the invention is adapted for use not only at railway freight terminals for the 85 handling and shipping of freight, merchandise, parcel post, express material, etc., or at shipping docks for steamboat transportation, but also in various manufacturing industries such as the automotive industry. 90 Automobile parts, including parts to be shipped to assembly plants in different sections of the country, or spare and replacement parts to be shipped to dealers, garages, etc., may be handled and shipped in the containers directly from the shipper to the consignee in accordance with the present invention. 95

The present application is a continuation in part of my applications Serial No. 184,384, 100 filed April 16, 1927, and Serial No. 199,099, filed June 15, 1927.

Where the shipping containers are transported upon a flat car, as shown for the purpose of illustration in the present case, flat 105 cars of standard construction may be used.

without necessitating any substantial reconstruction thereof. In the present case I have illustrated a relatively simple and effective manner of mounting the containers on the floor or platform of the flat car or carrier so that the containers will be supported against displacement during transit. The containers and the supporting means secured to the car floor for maintaining the containers in position during transit are so constructed as to enable the containers to be readily loaded or unloaded from the cars, easily locked in position when loaded or easily released to enable the container sections to be unloaded at designation. In one form illustrated herein the containers may be provided with leg supports which permit them to be picked up and transported from point to point upon the lift platform of a power driven lift truck, but in transporting the containers on the carriers, such as a railway flat car, the leg supports are preferably detached from the container so as to provide greater stability in transit on account of the shocks and collisions to which the cars are subjected.

In Figs. 1 to 8 inclusive I have shown one manner of mounting the shipping containers upon the floor or platform B¹ of a railway flat car or carrier B. The car is positioned upon railway tracks RR and contains a series or group of separate and individual shipping containers or sections each shown as a whole at C. Each container is a complete unit and is provided with doors at opposite ends together with a pair of walkways positioned above the roof of the container section. Together, the group of sections, when mounted upon the platform B¹ present the appearance of a complete box car.

Each of the container sections C is provided with a bottom or floor comprising cross board bound around the four edges by means of angles 20, a roof or top 21, side walls 22, 22, and end walls 23 each of which is preferably provided with swinging doors 24 and 25. The skeleton frame structure of each container section comprises, preferably, vertically extending angle bars 26 and 27 at the front and rear respectively of each side wall, these vertical members 26 and 27 being connected at their lower ends with the container section floor angle 20 by means of gusset plates 126 and 127 respectively, and supporting at their upper ends curved or substantially arch-shaped angles 28 which form supporting means for the top or roof 21 of the section, the angles 26, 27 and 28 being connected together by means of gusset plates 128. Extending substantially horizontally along each side wall 22 and preferably on the inner side of each wall, are a plurality of spaced angles 29, these angles being connected at their ends with the vertical angles 26 and 27 by means of gusset plates 129, one of which is provided for each

horizontal angle at its end portion. To brace the horizontal angles 29 and the angles 28, and to maintain them in spaced relation and likewise prevent sagging of the angles and roof 21, a vertically extending, preferably centrally positioned reinforcing strap or bar 30 is provided, the lower end being connected with the floor angles 20 and the upper end with the angle 28, the intermediate portion of the member 30 being connected with each of the horizontal angles 29. It will be noted that the upper end of the member 30 projects slightly above the roof structure 21 at the side thereof.

To additionally brace the container section, I provide a pair of metal tie bars 31, 32 which are secured at their lower ends to the gusset plates 126 and 127 respectively and to each of the horizontal angles 29 and likewise to the roof supporting angle 28. It will be noted that the bars 31 and 32 extend upwardly in converging relation and also that the upper ends of the bars project considerably above the roof 21 at substantially its transverse center. Connected with the upper projecting ends of the members 31 and 32 by means of rivets or the like are a pair of angle plates 33 and 34 having inwardly extending flanges 33^a and 34^a respectively, positioned back to back. Connected to the opposite outer faces of these flanges are a pair abutting channels 35, the web portions of which are positioned back to back to form a bail 36 for the container section. It will be understood that the several angles, gusset plates and tie bars herein referred to are connected together to form an integral structure, preferably by means of rivets, although it may be found desirable to employ bolts or other securing means for this purpose. The metal side walls 22, 22 entirely enclose the framework of the container.

Mounted upon the roof 21 of the section and rigidly connected therewith, is a transversely extending and preferably substantially centrally located walkway 40, this walkway comprising a pair of spaced angles 41 connected at opposite ends with plates or gussets 42, which plates or gussets are in turn connected with and supported by the roof supporting angle 28. The angles 41 are likewise connected with the brace members 30, 31 and 32 to prevent any possibility of sagging at the central portion thereof. Mounted upon the angles 41 in any suitable manner and likewise extending transversely of the container section, are a plurality of boards 43 which together form the walkway. By providing a series of boards 43 and positioning them at opposite sides of the converging upwardly projecting ends of the brace members 31 and 32 which support the bail 36, it will be noted that two separate and distinct walkways are provided. Likewise by so positioning the walkways, it will be understood that the bail 36 also serves as a hand hold or

supporting structure for the brakeman when walking along the top of the group of container sections forming the box car B.

In order to provide means for effecting a detachable connection between adjacent container sections at their upper portions and likewise to prevent any possibility of relative displacement of the containers when the car is in transit, each of the gusset plates 128 is provided with an extension or projection 128^a, which extension or projection is provided with a slot or aperture for the reception of a bolt as hereinafter described.

The doors 24 and 25 are pivotally connected with the end walls 23 of the container section by means of hinges 37 of any suitable construction. The door 25 is provided with a plate 25^a at its free edge, this plate being secured to the door and being adapted to over-lap the free edge of the door 24 when the doors are closed, as shown in the drawings. The door 25 is likewise provided with locking means in the form of a pair of reciprocal rods 25^b connected with a cam member 25^c which is pivoted at 25^d to the door. The cam member is provided with an operating handle or lever 25^e which, when the doors are closed, is adapted to engage and be supported by a slotted stop 24^a mounted upon the door 24. At the upper and lower edges of the door 25, guide members 25^f are provided which serve to support and maintain against accidental displacement, the rods 25^b. These guides likewise serve to cause the ends of the rods 25^b, when in their projected or operative position, to register with apertures formed in angle plates or keepers 23^a. This construction permits the doors to be simultaneously locked together to prevent any accidental or unauthorized opening of the doors, it being understood, of course, that the usual seal is applied to the operating handle or lever 25^e to maintain it against movement relative to the stop 24^a. The dual locking means permits the authorized opening of both doors by a simple and convenient operation.

The floor, including the angles 20, of each container section, is provided on its under side adjacent one longitudinal edge with a metal supporting plate 45. At the outer edge of each plate 45 there is provided a longitudinally extending plate or strip 46 which is maintained in spaced relation with respect to the plate 45 by means of a narrow filler strip 47 interposed therebetween. The plates 45, 46 and the strip 47 are all secured together and to the floor angles 20 by means of bolts 46^a. At the inner longitudinal edge of each plate 45 there is provided an angle bar 48 having a vertical flange 48^a and a horizontal flange 48^b, the latter flange being maintained in spaced relation with respect to the plate 45 by interposing between the flange and plate, a filler strip or bar 49. The members 48^b, 49 and 45 are secured together

and to the floor angles by means of bolts 480^b, which bolts are provided with countersunk heads so as to lie flush with the exposed surface of the flange 48^b (see Fig. 6). The flange 48^a of each angle 48 is provided adjacent its opposite ends with a hole or slot 480^a. It will be seen, therefore, that by so positioning the plate 46 and the angle 48 and maintaining them in spaced relation with respect to the plate 45, a longitudinal guideway or channel 50 is provided at each under side of the container. It will be noted (see Fig. 3) that the guideway or channel construction at each longitudinal edge of the under surface of the floor is identical.

The guideways or channels 50 are provided for the purpose of supporting, when desirable, detachable leg members indicated as a whole at 55 in Fig. 4. Each container section is preferably provided with four leg members, there being a pair of such members removably supported by the guideways or channels at each longitudinal side of the floor. Each leg 55 comprises a vertical channel 56 having parallel flanges 56^b and a central web 56^a which is rigidly connected adjacent its upper end with the vertical flange 57^a of a relatively short angle bar 57 by means of rivets 560^a, the flange and the web being positioned back to back. The horizontal flange 57^b of the angle 57 overlies and is in engagement with the upper end of the channel. The angle 57 is of sufficient length to extend considerably beyond the parallel flanges 56^b of the channel. Mounted upon the horizontal flange 57^b and supported thereby is a plate 58, the plate being connected with the flange in any suitable manner. A brace member 59 in the form of a bar which is bent to provide a foot portion 59^a and upwardly and outwardly flared portions 59^b, having at their upper free ends out-turned portions or flanges 59^c, is connected with the channel and the flange 57^b by means of rivets 590^b and 590^c, respectively. The vertical flange 57^a is provided adjacent each end with an aperture or slot 570^a adapted to register with any one of the holes or apertures 480^a provided in the vertical flange 48^a of the angle bar 48, when the parts are in the position in which they are shown in Figs. 5 to 8 inclusive, thus providing standard legs which are interchangeable.

To apply the legs or supporting members to a container section it is merely necessary to insert the plate 58 of the leg in the guideway or channel 50, slide it into place, and bring the apertures or holes 480^a and 570^a of the respective members into register. When in this position a bolt 15 having a countersunk head 15^a is inserted into the holes and a nut 16 applied thereto, thus preventing the accidental displacement of the leg member.

When the container sections C are supported upon the car floor B¹ as shown in Figs. 1 and 2, it will be seen that the detachable legs

are removed. For the purpose of supporting each container section upon the car floor and maintaining it against relative longitudinal movement thereupon, a series of pairs 5 of transversely disposed spaced apart members are provided. These members in the present instance each comprises an angle bar 60 having a horizontal flange 60^a detachably mounted upon the car floor by means of bolts 61, and a vertical or upstanding flange 60^b. The flanges provide means for receiving and supporting a wood block 62 which is detachably connected with and secured to the vertical flange 60^b by means of a series of bolts 15 62^a, the heads of which are countersunk so as to lie flush with the outer face of the flange. The space between each pair of supporting members of a container section is determined by the space between the angles 48 carried at 20 the under side of the container section floor and is governed by the size of the container section. When a container is placed upon the car floor B¹ and supported by the angles 60 and the blocks 62, it will be seen that the vertical or depending flanges 48^a lie outside and in abutting relation to the vertical flanges 60^b. A bolt 63 is provided at each side of the container section (Fig. 2) and is inserted through the hole 480^a formed in the vertical 25 flange 48^a and in a similarly pre-located hole or slot provided in the vertical angle 60^b and the wood block or strip 62, to hold the parts in fixed relation and maintain the container section in position upon the car floor B¹. A 30 nut 64 is threaded upon the end of each bolt to maintain it in position. In order to maintain adjacent sections in position at their upper portions and to restrict their relative movement and accidental displacement during transit, I provide a bolt and nut 65 which 35 is adapted to be inserted through the slot or aperture formed in the projecting portions or ears 128^a of adjacent sections. Thus it will be seen that when the container sections are 40 in position upon the car floor, they are maintained against accidental displacement relatively thereto.

From the foregoing it will be seen that the 45 means provided upon the under side of each container section floor performs a dual function, namely that of maintaining the containers in position upon the car floor or platform B¹ and restricting their relative displacement when the car is in transit, and also 50 serve as means for receiving and supporting the detachable leg members 55 when the container section is removed from the car. The method of removing or unloading the container sections from the car or loading them 55 upon the car, as well as the improved apparatus for performing the method, has been 60 fully shown and described in my co-pending application, Serial No. 173,761 filed March 8, 1927.

65 It will be understood that when the con-

tainer sections C are supported by the detachable and interchangeable legs 55 (Fig. 5) a lift truck platform may be moved in position to underlie the container section floor within the area between the detachable legs, so that 70 the section may be lifted and transported thereby.

In Figs. 9 to 13 inclusive I have shown a modified form of shipping container which is particularly adapted for use in connection 75 with my standard portable platforms of the character disclosed in my Letters Patent No. 1,608,039 issued November 23, 1926, which platforms serve to support the container sections when removed from the freight car and 80 facilitate the handling of the sections at railway landing or loading docks.

In the modified form of my invention the structural features with the exception of the container floor and supporting structure 85 thereof and the means for locking the containers in position upon the freight car and to one another, are identical with those shown in Figs. 1 to 8 inclusive.

The flat freight car B shown in Figs. 9 and 10 is provided with the usual floor or platform B¹. Mounted upon the floor and extending longitudinally thereof adjacent each edge is an angle bar D having a horizontal flange D¹ secured to the car platform by 95 means of bolts or the like E, and a vertical or upstanding flange D². The angle bars D are provided for the purpose of preventing the accidental lateral movement or displacement of the container sections when the car is 100 in transit. Each angle bar is provided at pre-determined spaced intervals with container section guiding and securing or locking means in the form of units F to be fully described hereinafter.

In addition to providing the gusset plates 128 with projections or ears 128^a as shown in Fig. 2, the gusset plates 126 and 127 of the container section of Figs. 9 to 13 inclusive are 105 also provided with projections or ears 126^a and 127^a respectively, which project through the end walls 23 and are provided with slots or apertures.

In the construction shown in Figs. 11 to 13 inclusive, the floor boards 122 of the container 115 are supported around the four marginal edges of the floor by means of angle bars or truss members 120. These angle bars are rigidly connected at the four corners of the container to the upright angle posts 26 and 27, and also 120 to the tie bars 31 and 32, by means of the gusset plates 126 and 127. The horizontal flanges 120^a extend inwardly from the container walls and provide means for supporting the floor 125 boards 122. The floor boards are secured to the horizontal flanges 120^a by means of bolts or the like 123 having countersunk heads so as to lie flush with the under surface of the flange 120^a. The nuts 124 when threaded upon the bolts 123 lie within countersunk re- 130

cesses or depressions 122^a formed in the upper surfaces of the boards 122.

By providing the floor angles 120 and connecting them to the bail structure 36 through 5 the medium of the tie bars 31 and 32 and the gusset plates 126 and 127, it will be understood that the lifting strains and stresses will be equally distributed throughout the structural steel framework of the container sections and 10 to the angles 120 beneath the floor boards 122.

In order to guide the container sections when being lowered into position upon the car floor or platform B¹, and likewise to lock such sections in place against accidental dis- 15 placement when the car is in transit, I provide the units F, previously referred to.

In Fig. 13 I have shown in detail a pair of such container section guiding and locking means mounted upon one of the angle bars 20 D. Each angle bar is provided at pre-determined spaced intervals with a pair of units F including a pair of vertically disposed plates or gussets 50 each of which is positioned back to back with one face of the vertical or up- 25 standing flange D², preferably the inner face of the flange, and secured thereto by means of rivets or the like 51 to form an integral part of the angle bar. Each plate or gusset supports a relatively short angle bar 52 hav- 30 ing a flange 52^a which is positioned back to back with the outer face of the plate or gusset and secured thereto by means of rivets or the like. The angle bar 52 is also provided with an outwardly projecting portion or flange 35 52^b having a slot or aperture 520 therein. The upper end of the angle 52 is curved as shown at 152 to provide a cam surface or guide means for the ear or projection 126^a or 127^a of the container section when the sec- 40 tion is being lowered into position upon the car floor or platform B¹. The flanges 52^b of the short angles 52 are opposed or in jux- taposition and spaced apart sufficiently to permit the entry therebetween of the ears 45 126^a or 127^a when a container section is being lowered into position upon the car floor. It will be understood that the location of the units F along the angle bars D is determined by the size of the container sections. It will 50 also be understood that a single unit F is mounted upon the longitudinal angle bar D at each end thereof (see Fig. 9) since it is only necessary to employ a pair of such units at the intersection of adjacent container sec- 55 tions as shown in Fig. 13. If desirable the plates 50 and angles 52 may be secured together to form the units by means of spot welding. After the container sections have been lowered into position upon the car floor 60 or platform as shown in the drawings, with the parts in their operative relations as shown in detail in Fig. 13, a bolt 125 is inserted through the several aligned apertures or slots provided in the angles 52 and the 65 ears 126^a or 127^a, as the case may be, and

a nut applied thereto to lock the parts in position against relative movement or displacement when the car is in transit.

From the foregoing it will be understood that the container section guiding and locking means in the form of the units F are preferably positioned in pairs along the longitudinal angles D where adjacent containers are to be locked together upon the car floor, whereas it is only necessary to provide 75 a single unit at opposite ends of the angles D.

It will also be understood that by providing the relatively short angles 52 of the units F with curved upper ends, they serve to 80 guide or direct a container section into its proper position upon the car platform B¹ when it is being lowered into position to be supported thereby. It will be seen that the units F thus provide relatively simple means for guiding the container sections into 85 position upon the car platform and likewise serve as means which cooperate with the ears or projections on the container sections for locking the parts together.

Where containers of the form shown in 90 Figs. 9 to 13 inclusive are employed, they are preferably supported when not in transit on the freight car by means of portable platforms previously referred to, one of which is shown at P in Fig. 11.

I claim:

1. A shipping container comprising a load supporting floor and side walls, structural angle bars embracing opposite edges of the floor and having horizontal flanges extending beneath the floor, diverging tie bars at opposite sides of the container connected to said angle bars, and a transverse lifting bail connecting the upper ends of said tie bars.

2. A shipping container comprising a load supporting floor, floor framing angle members having flanges extending beneath the floor, roof framing angle members, upright corner posts connecting said angle members at the four corners of the container, side walls and a roof enclosing said framework, an overhead lifting bail extending centrally above said roof, and a pair of diverging tie bars at each side of the container connecting said bail and floor framing angle members.

3. A shipping container comprising a load supporting floor and side walls, structural angle bars embracing opposite edges of the floor and having horizontal flanges extending beneath the floor, diverging tie bars at opposite sides of the container connected to said angle bars, a transverse lifting bail connecting the upper ends of said tie bars, and a walkway extending transversely above said side walls and secured to said tie bars.

4. A shipping container comprising a load supporting floor and side walls, structural angle bars embracing opposite edges of the floor and having horizontal flanges extending beneath the floor, diverging tie bars at oppo-

site sides of the container connected to said angle bars, a transverse lifting bail connecting the upper ends of said tie bars, and a walkway extending transversely above said side walls at each side of said bail.

5. A shipping container comprising a load supporting floor and side walls, a roof mount-

ed above said side walls, a transverse centrally located lifting bail mounted above said roof, and a board walk supported beneath said bail at each side thereof and extending parallel thereto.

In testimony whereof I affix my signature.
ROBERT T. ROMINE.
